US0D1096831S

(12) **United States Design Patent** (10) Patent No.: **US D1,096,831 S**
(45) Date of Patent: ** Oct. 7, 2025

(54) **DISPLAY SCREEN OR PORTION THEREOF WITH GRAPHICAL USER INTERFACE**

(71) Applicant: **Samsung Electronics Co., Ltd.**, Suwon-si (KR)

(72) Inventors: **Yoonjung Oh**, Suwon-si (KR); **Joosun Moon**, Suwon-si (KR); **Min-Kyung Lee**, Suwon-si (KR); **Kyeong-A Han**, Suwon-si (KR); **Junpyo Hong**, Suwon-si (KR)

(73) Assignee: **SAMSUNG ELECTRONICS CO., LTD.**, Gyeonggi-Do (KR)

(**) Term: **15 Years**

(21) Appl. No.: **29/940,318**

(22) Filed: **May 1, 2024**

(30) **Foreign Application Priority Data**

Nov. 7, 2023 (KR) 30-2023-0043681

(51) LOC (15) Cl. **14-04**

(52) U.S. Cl.

USPC **D14/487**

(57) **CLAIM**

The ornamental design for a display screen or portion thereof with graphical user interface, as shown and described.

DESCRIPTION

The FIGURE is a front view of a display screen or portion thereof with graphical user interface showing our new design.

The outer perimeter shown by a pair of dashed broken lines in the drawings represents the display screen or portion thereof and forms no part of the claimed design.

The remaining dashed broken lines shown in the drawings illustrate portions of the graphical user interface that form no part of the claimed design.
